A-FRAME CONSTRUCTION

Bart M. Jacob, West Dover, Vt., assignor, by mesne assignments, to Bart M. Jacob, West Dover, Vt.

Filed June 4, 1962, Ser. No. 199,693

6 Claims. (Cl. 50—64)

This invention relates in general to building construction and more particularly to the construction of an A-frame house from prefabricated panels.

There are several important factors involved in the construction of a building. The building itself must be structurally and mechanically strong, while containing a limited number of supporting members within the enclosed area in order to provide for the freest possible planning of the interior layout. Additionally, the building must be capable of withstanding the natural elements and must provide insulation in order to maintain the temperature within the enclosed area less variable than the temperature of the surrounding environment. Another factor is the process of construction itself. In recent times, the use of prefabrication and preassembly techniques has greatly increased the efficiency of this process and materially reduced the cost of construction. Prefabrication of portions of the buildings to be constructed at off-site locations permits some of the advantages of mass production to be utilized in building construction. Thus, portions of similar buildings, which are to be located at diverse geographical points, may be fabricated at a single location, allowing production of a "run" of identical parts which are to be used in the different buildings.

In addition, the farther this prefabrication and preassembly can be carried, the simpler the construction process at the site becomes and personnel involved in the assembly construction process need not have the diversity of skills formerly required when the entire construction was carried out at the site. In this prefabrication and preassembly process, the larger the portion of the building which may be prefabricated, in general the easier is the construction process at the site. Additionally, the process is rendered more efficient if the building to be constructed can be formed of a plurality of basic modules such that larger buildings involve, not a change in the prefabricated elements, but merely a greater number of these same elements.

One form of building design, which provides a basically sound structure and has found use in small homes, small commercial buildings, and the like is that design generally referred to as an "A-frame building." In this design, two opposite side walls are inclined inwardly and carried in an unbroken line to the roof peak thereby forming side walls and roof with the two remaining walls forming the gable end. The usual method of construction for such a building is to erect upon a base platform a frame consisting of rafters which are attached at the upper end to a ridge pole and supported at the base end upon the platform. This framework is then sheathed in conventional fashion.

The forces upon the structural members in this situation are both vertical and horizontal. Thus, at the junction between the rafters and the base platform, the rafters must be not only supported vertically but also must be prevented from horizontal outward movement. One method of providing this horizontal restriction is the use of a "collar beam" which ties opposed rafters on either side of the ridge pole to one another, thus giving the structure, viewed from the end, the form of the letter A with the collar beam forming the cross bar of the A. Further tying against this horizontal force is provided by driving nails angularly through the sides of the rafters close to the platform so that they penetrate into the platform.

2

At the ridge pole, the horizontal forces on one rafter are counterbalanced by the opposed horizontal forces from the opposite rafter while the vertical forces are counteracted in part by either angular nailing or nailing through the ridge pole into the butt end of the rafter on the opposed side of the ridge pole. The resulting structure is sound and capable of withstanding the natural elements. However, its construction requires skilled craftsmen and is time consuming since the pieces must be cut and secured in place one by one.

Accordingly, the primary object of this invention is to provide an A-frame building formed of a plurality of like modules which can be erected at the site in a matter of hours using only a few workers.

15 A more specific object is to provide a building construction for an A-frame unit employing prefabricated panels which include the structural beams as an integral part thereof and in which the ends of the structural beams are precut in such a fashion as to form an interlocking 20 mechanical joint when the panels are assembled to form the structure.

25 Still another object of the present invention is to provide a building construction for A-frame buildings employing prefabricated panels which include the structural beams, the sheathing, and insulating in an integral unit.

It is yet another object of the present invention to provide a building construction for A-frame buildings employing prefabricated panels as a module unit whereby the size of a building may be extended by increasing the 30 number of panels employed.

Other objects and advantages will become apparent from the following detailed description when taken in conjunction with the accompanying drawings in which:

FIG. 1 is a perspective view of an A-frame house constructed in accordance with the principles of this invention;

FIG. 2 is a perspective view of a partially assembled A-frame house embodying the principles of this invention, portions of the house being cut away to show details of its 40 interlocking joints and panelled construction;

FIG. 3 is a cross-sectional view taken along line 3—3 of FIG. 2;

FIG. 4 is a cross-sectional view taken along the line 4—4 of FIG. 2;

45 FIG. 5 is a cross-sectional view taken along line 5—5 of FIG. 2; and

FIG. 6 is a perspective view of a floor panel formed in accordance with the principles of this invention, a portion of the panel being cut-away to show its internal construction.

With reference now to FIGS. 1 and 2, the A-frame house 10 embodying the present invention is shown mounted on a cinder block foundation 12. However, the house does not require any special form of foundation but may be constructed on almost any kind of conventional support, whether of the enclosed wall type or open post type. The A-frame house of this invention is formed by the assembly of two types of prefabricated panels; floor panels 14 and roof panels 16. The panels 55 may be directly assembled to form the structure without the necessity of erecting an independent frame. Both the floor panels and roof panels are similarly constructed, the chief differences lying in the provision of means at the ridge end of the roof panels for forming an interlocking outer sheathing. Each of the panels includes sheathing formed of plywood, structural members formed from wooden beams, and insulation such as exploded semi-rigid polystyrene or polyurethane foam or fiberglass bats.

60 The detailed construction of each of these panels is most clearly seen from the views of FIG. 2 and FIG. 6. The floor panels are shown to include a basic ladder-like structure comprising elongated side members 20 and

shorter cross members 21. Preferably, the ladder-like structure is made of 2 x 4's. Firmly attached to each of the side members 20 are the main structural beams 22 and 23 of the panels. Preferably, these beams are formed from 2 x 8's. Each panel also includes separate layers of sheathing 25 and 27 attached to the upper and lower side of the ladder-like structure. Preferably, the sheathing is plywood, typically with a thickness of $\frac{3}{8}$ inch. The upper sheathing is extended over the upper edges, i.e., flush with the sides, of the main beams 22 and 23. However, bottom sheathing 27 is inset with respect to the bottom edges of the beams 22 and 23, extending only to the inner sides thereof as shown in FIG. 3. The spaces in the ladder-like structure enclosed between the sheathing members 25 and 27 are filled with an insulating material 30, preferably a plastic foam 30 such as exploded polystyrene or polyurethane.

The structural beams 22 and 23 are generally coextensive with the side 2 x 4 members 20. However, each of the beams 22 and 23 extends at one end beyond the side members 20 and at the opposite end does not extend as far as the 2 x 4 elements 20. This configuration can be most clearly seen in FIGS. 4 and 6. Each beam 22 extends beyond its abutting side member element 20 at the same end at which the other beam 23 falls short of the length of its abutting side member 20. Each end of beams 22 and 23 is cut at an angle measuring approximately 60° with its underneath edge. These angular cuts taken together with the extension of the beams beyond the end of the panel "core" (referred to for convenience as that portion of the panels lying entirely within and including the ladder-like structure) form upon assembly of the floor and roof panels an interlocking mechanical joint, as will be explained below in detail.

The roof panels 16 differ from the floor panels 14 in the formation of the upper sheathing 25; the direction of the angular cut on the carrying beams and in the length of the core.

On the floor panels the upper sheathing 25 extends at either end only as far as the inner core of the panel and terminates at the outer edge of the end 2 x 4 cross member 21. In addition, this sheathing is notched at each of the upper corners. On those corners where the carrying structural beams 22 and 23 are shorter than their abutting 2 x 4 members 20, the upper sheathing 25 is cut away permitting free access from above to the slanted end face of the carrying beams. On the two corners where the carrying beam members 22 and 23 extend beyond the end 2 x 4 cross members 21, the upper sheathing 25 is cut back to expose a small portion of the flat upper edge of these beams. As will be described below, these notches in the upper sheathing 25 allow the ends of the carrying beams 22 and 23 of the roof panel to be attached securely to the carrying beams 22 and 23 of the floor panels.

In the roof panels, the upper sheathing 25 not only does not have these notches, but also is extended at the upper end beyond the 2 x 4 cross member 21 to within $\frac{3}{4}$ of an inch of the upper end of the 2 x 8 carrying beam 23. At the lower end of the roof panel, the sheathing member 25 projects beyond the end cross member 21 of the core section by approximately $\frac{3}{4}$ of an inch. It should be noted that in the roof panel the core extends at the lower edge as far as the extended carrying beam 22. The other significant difference between the floor panels 14 and the roof panels 16 is that, in the case of the roof panels, the angular cut is at an angle of approximately 60° with the upper edge of the 2 x 8 beam members 22 and 23.

Typical dimensions for these panels are a width of 4' with a length of 24'. It will thus be noted that assembly of six roof panels with three floor panels forms a structure having a base dimension of 12' x 24', while a structure involving twelve floor panels and twenty-four

5 roof panels would provide a structure having a base of 48' x 24'.

With reference now to FIG. 2, the manner in which these panels 14 and 16 are assembled to form an A-frame structure is illustrated. It should be understood that each floor panel is supported upon the foundation and then the two roof panels forming the left- and right-hand side are raised above it. At the junction between each two roof panels on the same side of the roof peak, the adjacent 2 x 8 beams together form a rafter. These beams, which are the right-hand beam 23 of one panel and the left-hand beam 22 of the next panel, are different in length. The left-hand beam 22 extends beyond the core at the upper end while the right-hand beam 23 falls short of it. In the opposed panels forming the opposite side of the A-frame, the position of these two beams is, of course, reversed. Thus, the upper end of each beam 23 of a left-hand panel butts against the underside of the extended position of beam 22 from the opposite panel. The interlocking joint is then as shown circled at "A."

When the two panels side by side are erected, their adjoining beam members 22 and 23 are fastened together along their length, either by nails or bolts (not shown). In addition, the extended portions of the beams 22 from the left-hand and right-hand panel members forming the A are fastened together by nails 36 (or bolts) at the point where they extend beyond the core and overlap one another (FIG. 4). The joint thus formed and illustrated at "A" provides, then, vertical support for both left- and right-hand panels by means of the beams 23 butting up against the underside of the beams 22, and since the joint is a double joint, involving the ends of two beams 22 and two beams 23, horizontal tying in both left- and right-hand directions is provided.

A similar double interlocking joint is provided at the platform end of the roof where the roof panels join the floor panels. Thus, it will be noted that the beams 23 of the roof panels extend below the top of the floor panels while the beams 22 of the roof panels are cut off short of the end of the core of the roof panels in a position to rest on the top of the extended floor panel beam 22. The beams 23 of the roof panels fit along the slanted end face of the short end of the floor panel and overlap the outside face of the extended portion of the floor beam 22 of the next adjoining floor panel. These overlapping portions are fastened together by nails 38 (or by bolts) into this overlapping portion. This type of interlocking joint is shown in the circle at "B." In the lower joint again vertical support is provided by the butting of the roof panel beam 22 against the top of the floor panel beam 22 while (a) inward horizontal movement is prevented by the butting of floor beam 22 against roof beam 23 and (b) outward horizontal movement is prevented by the direct tying of roof panel beams 23 to the floor panel beams 22 of the next adjoining panel.

When the requisite number of panels for the size of the structure has been assembled in the manner described above on a suitable foundation, the only remaining construction work required on site is the finish details at the bottom edge of the roof panels and at the lower portion of the junction between the floor and roof panels, the erection of suitable gable ends, and provision of suitable roofing material over the roof panel sheathing. The conventional method for finishing off the joint between the roof panel and the floor panel is best illustrated in FIG. 5. The crevice between the end of the floor panel 14 and the lower side of the roof panel 16 is filled with a fiberglass insulation 50 which is held in place with a trim board 51 formed from material such as 1 x 4 wood. At the lower end of the roof panel, a 1 x 8 fascia board 52 is fastened along the length of each side.

The structure then is basically formed of two very similar types of panels; floor panels and roof panels. These two basic modules may be fabricated at a production location and transported to the site of construction.

Each panel contains sheathing, structural beams and insulation, and, upon erection, provides a structure which has interior and exterior sheathing, structural framing members and complete insulation. The double interlocking joint construction of the carrying beam portion of the panels provides for complete mechanical strength against both horizontal and vertical forces, and the only operation (except for the gable ends) required to be performed in the assembly of this structure is the fastening of the panels to one another.

Having described the invention, various modifications and improvements will now occur to those skilled in this art, and the invention disclosed herein should be construed as limited only by the spirit and scope of the appended claims.

What is claimed is:

I claim:

1. An A-frame building formed of a group of modules comprising, a pair of floor modules, a first pair of roof modules and a second pair of roof modules, each of said modules including first and second beams and a core disposed between and attached to said first and second beams forming a panel having first and second ends, each of said beams having corresponding first ends located on said panel first end and second ends located on said panel second end said first beam having its first end projecting beyond the first end of the second beam and said second beam having its second end projecting beyond the second end of said first beam, said modules being disposed in a triangular arrangement such that at each junction between four modules, the respective module beams form an interlocking joint wherein the first end of the first beam of each module is supported upon the first end of the second beam of another module and wherein the beams of each module are secured to the beams of one other module, said floor module beams being connected to the second ends of said roof module beams.

2. A building in accordance with claim 1 wherein said core includes a pair of parallel sheathing members and insulating material enclosed between said pair of sheathing members.

3. A building in accordance with claim 1 wherein said beam ends are beveled such that a smooth joint is formed when said beams are interconnected at a 60° angle.

4. An A-frame building having a floor and a roof supported by and secured to said floor, said floor and roof each being formed of a plurality of substantially identical modules wherein each module includes first and second beams and a core disposed between and attached to said first and second beams, said core having first and second ends, said beams having corresponding first and second ends, said first beam having its first end projected beyond the first end of the second beam and said second beam having its second end projected beyond the second end of said first beam and wherein said roof comprises two groups of modules having the first ends of their beams engaging and supporting each other such that the first end of the first beam of each module in each group extends past and is supported by the first end of the second beam of a module in the opposite group and is secured to the first end of the first beam of a module in the other group, and wherein said groups of roof modules have the second ends of their beams attached to opposite ends of said floor modules.

5. A building in accordance with claim 4 wherein said core includes a pair of parallel sheathing members and insulating material enclosed between said pair of sheathing members.

6. A building in accordance with claim 4 wherein said beam ends are beveled such that a smooth joint is formed when said beams are interconnected at a 60° angle.
